UNITED STATES PATENT OFFICE.

WILLIAM B. BEMENT, OF PHILADELPHIA, PENNSYLVANIA.

IMPROVEMENT IN STANDS FOR MACHINES.

Specification forming part of Letters Patent No. 35,433, dated June 3, 1862.

To all whom it may concern:

Be it known that I, WILLIAM B. BEMENT, of the city of Philadelphia, in the State of Pennsylvania, have invented a new and useful Improvement in Machinery; and I hereby declare that the following specification, in connection with the accompanying drawings and letters of reference marked thereon, constitute a lucid, clear, and exact description of the construction and use of the same.

In referring to the said drawings, Figure 1 denotes a front elevation of a vertical milling-machine with my improvements applied thereto; embodied therewith, and embraced therein; Fig. 2, a side elevation of the same; Fig. 3, a front elevation of a bolt - threading machine constructed in accordance with and embracing my improvements. Fig. 4 denotes a side elevation of a shaping-machine having my improvements applied thereto.

My invention is obviously applicable to a great variety of machinery; and its nature consists in constructing the supporting-structures of machines with a cabinet or tool-receptacle formed therein by casting them in one entire piece, for adding an important utility, as well as great strength and durability, to any machine to which it is applied, and without increase of expense, all as will be hereinafter seen.

To enable persons skilled in the art to which my invention appertains to construct and carry out the same, I will proceed to describe it as follows, after first stating that my invention is applicable to a great variety of machines.

The supporting-structures for the machines shown in the drawings are seen at A, B, C, and D in each of the figures. The supporting-structure is to be cast in one piece entire and in any form desired which will be suitable to receive the various movements of the machine, and to add great strength and combine elegance and beauty in its appearance, and at the same time not add to its expense and saving the cost of tool - chests, a suitable pattern is made, and of the form which the supporting-structure is to be cast, so that the same may be nicely molded and cast by any competent foundryman.

The cabinet or tool-holder may have shelves cast therein, as seen at a a', or apartments otherwise arranged for adding great strength to the machine, to prevent recoil when in use,

and to receive and hold all the tools and implements used about the machine, thus saving the time of machine and trouble of operator frequently running from machine to bench and other parts of the shop in search of tools, always lost in the old way, and always in place where my within-described improvement is adopted, by there being a convenient place to receive them and everything in its place. Thus each machine has all its tools for its use in the most convenient place—that is, within the machine itself—and in utilizing space therefor, which has been heretofore useless.

A door, seen at b c d e, is to be cast and suitably hinged, as seen at i, to the supporting-structure to neatly inclose the cabinet, add beauty to the machine, and for exclusion of dust, and which may also be provided with an efficient lock for the safe-keeping of the tools and implements stowed therein and for protecting them from fire.

It will be seen that by my invention the various portions of the supporting-structure may be of less thickness and weight, and yet more substantial, than old machines with usual strength, which is resultant from the various bracing shapes susceptible of being imparted solidly to the supporting-structure. The necessary partitions which are cast in the cabinet add both convenience and strength to the supporting-structure by reason of solidly uniting the shelves, sides, partitions, and ends of the supporting-structure in one entire piece.

The use of my invention is obvious from the preceding description of construction, and consequently leaves for further exemplification its advantages, some of which consist, first, in the obvious utility in the supporting-structure of a cabinet or tool-receptacle all cast in one piece; second, in always having the tools used in operating the machine in the cabinet and most convenient place and nearest to where they are actually used; third, in adding great strength to the supporting-structure; fourth, in rendering the machine more substantial and less liable to recoil in doing heavy work with less weight of iron in construction; fifth, in improving and beautifying the entire machine in which my invention is incorporated; sixth, by increase of shelves and partitions the greater is the strength of supporting-structure; seventh, in saving the expense of tool-chests and their room on the benches and floors of

shops; eighth, in rendering room about shops heretofore used for tool-chests useful for other purposes; ninth, in preventing the hinderance and inconvenience of tool chests or holders about the shops; tenth, in the tool-cabinet occupying no extra room, and being embodied in the supporting-structure without enlargement of required room for the machine, thereby and consequently utilizing space heretofore useless; eleventh, in constituting the machine a safe in which its tools are secure from loss or damage by fire; twelfth, in lessening the price of insurance on the many valuable tools used in various manufacturing establishments; thirteenth, in embracing all these important

advantages in one and the same machine without additional expense thereto. Other advantages might be named which are resultant from my invention.

Having thus described my invention, I will state my claim as follows:

The main supporting-structure of machines, having a cabinet or safe tool-receptacle formed therein when cast in one entire piece, essentially in the manner and for the purposes set forth and described.

WM. B. BEMENT.
